CLAIM

The ornamental design for a solar panel roof pedestal, as shown and described.

DESCRIPTION

FIG. 1 is a front elevation view of a solar panel roof pedestal.
FIG. 2 is a top view.

FIG. 3 is a rear elevation view.

FIG. 4 is a bottom view; and,

FIG. 5 is a side elevation view.

The broken away symbols in the drawings indicate the appearance of any portion of the article between the break lines and forms no part of the claimed design.

1 Claim, 3 Drawing Sheets
